BURIAL VAULT

Filed Jan. 18, 1932

BY
Lockwood Lockwood Goldsmith + Galt.

ATTORNEYS.

UNITED STATES PATENT OFFICE

FLOYD L. TEMPLE, OF TERRE HAUTE, INDIANA

BURIAL VAULT

Application filed January 18, 1932. Serial No. 587,207.

This invention relates to a burial vault and the sealing therein of a casket.

When a wooden casket is employed, a metal container is preferably associated therewith. When a metal casket is employed and the same is the present tendency, the metal container is omitted.

The chief object of the invention consists in forming an air chamber around the side walls of the casket, an air chamber therebeneath which may or may not be in communication with the side wall encompassing air chamber, and an overhead air chamber sealed from the before mentioned air chambers and simultaneously with the sealing of the encompassing concrete burial vault when the cover thereof is applied to the body of the vault.

The chief feature of the invention consists in forming in the inner side wall of the burial vault adjacent the upper end or the mouth thereof a shoulder, and forming upon the cover for said vault a downwardly extending peripheral flange or tongue and then associating with the cover and the vault body a cement seal that, when associated therewith and with the casket or the metal cover, forms the air chambers previously mentioned and thereby protects the casket against condensation forming thereon and, therefore, subsequent deterioration or disintegration.

The full nature of the invention will be apparent from the accompanying drawing and the following description and claims:

In the drawing, Figure 1 is a transverse sectional view through a burial vault structure embodying the invention and wherein a metal casket is included. Figure 2 is a longitudinal sectional view taken at right angles to Figure 1 and of the same parts. Figure 3 is a transverse sectional view of a modified form of the invention and one wherein a metal casket is employed. Figure 4 is a view similar to Figure 3 and of a modified form of the invention showing the same associated with a wooden or non-metallic casket. Figure 5 is a view similar to Figures 1, 3 and 4 but of a simplified and modified form of the invention.

In Figures 1 and 2 of the drawing, 10 indicates the bottom of a concrete vault, 11 the

side walls thereof and 12 the end walls. Herein the end walls are illustrated as having an outwardly directed or flared upper end 13. Any desired reinforcement may be embodied in the vault. A cover 14 is provided which may be of natural or artificial stone or may be of concrete or a similar material. If desired, the same may have formed thereon a plate 15 that is of less area than the main body of the cover and may also have formed thereon the name plate or marker 16a. Where head stones are utilized the same may be substituted for the name plate or marker 16 and the head stone may be supported by the cover. The foregoing general arrangement forms no part of the present invention and is specifically disclaimed herein.

Positioned within the body of the vault is a suitable bottom support arrangement indicated by the numeral 16 and mounted thereon is the metal casket having the side walls 17, the top 18 and the connecting curved portions 19. The metal casket does not fully occupy the vault but is spaced from the side and end walls and is spaced from the bottom of the portion 16 or the equivalent.

Near the upper end and upon the inside of the side and end walls of the vault in Figures 1 and 2, there is formed a shoulder 20 and the inside wall is continued upwardly in the present instance by being inclined as at 21. Resting upon the shoulder 20 there is, as illustrated in Figures 1 and 2 of the invention, an angle iron enveloping structure 22. In Figures 1 and 2 of the invention there is illustrated, depending from the underside of the cover 14 of the vault and spaced inwardly an appreciable distance from the peripheral edge, a peripheral flange or tongue 23.

After the casket has been placed in the vault and the portion or portions 22 positioned, there is supplied to the vault around the open mouth thereof and adjacent the side and end walls a considerable amount of relatively dry cement material for forming a seal. In other words, the moisture content of the cement is insufficient to permit the body of the cement to escape between the portions 100

22 and the side and end walls of the vault or between the portions 22 and the casket.

When the cover is placed on the vault, the tongue 23 seats in the soft cement material 5 and the same gouges the material laterally in both directions so that there is formed a seal between the portions 18 and 19 and the top 14 and a seal is also formed between the cover 14 and the top edge of the side and end walls 10 11 and 12. This provides air chambers 25 around the casket and a top air chamber 26, the two not communicating with each other by reason of the seal. The seal also serves to seal the cover to the body of the vault.

15 In Figure 3 of the drawing, there is illustrated a modified form of the invention wherein similar parts are indicated by similar numerals of the 100 series. In this form of the invention, the side wall portion 121 and 20 the shoulder are combined in the form of a corrugated surface and nested in one of the corrugations determined by the size of the casket is the seal retaining member and chamber forming member 122 which may be 25 angular, as shown in Figures 1 and 2 but which preferably is shown as inclined so that a pressure fit is obtained between the side wall of the casket and the inner side wall of the vault when the pressure of the cover is 30 applied to the cement seal by reason of the weight of the cover bearing thereon. The tongue 123 extending into the cement material forms a seal between the top edge of the side and end walls of the vault and the cover 35 and also forms an air chamber at the top of the vault and in separated relation to the peripheral or side wall chamber arrangement shown therein.

40 In Figure 4 there is illustrated a modified form of the invention and in this figure similar or like parts are indicated by similar numerals of the 200 series. In this form of the invention, the wooden casket, the outline of which is indicated by the numerals 217, 45 218 and 219, is enclosed within a metal shell or side wall 240 and rests upon the support 216. The shoulder 220 of the side and end walls supports a frusto-conical metal member having the inclined faces 222 and the same 50 terminates in a top 241. The vault top includes the peripheral depending tongue 223 and, after the casket has been placed within the metal shell 240, the metal portion 222—241 is placed over the same until the lower edges 55 of the portion 222 rest upon the shoulder and preferably engage the top of the peripheral member 240. The cement material is compressed downwardly and laterally in both directions relative to the peripheral depending tongue 223 and seals the casket in the vault and also seals the cover of the vault to the body side and end walls, thereby forming the two air chambers 225 and 226 substantially similar to the chamber before mentioned.

In the respective figures the main body of the cement seal is indicated by the numerals 50, 150 and 250. The seal between the cover and the top edge of the vault is indicated by the numerals 51, 151 and 251, while the seal 70 between the tongue and the top member or structure to form the upper air chamber is indicated by the numerals 52, 152 and 252.

75 In Figure 5 there is illustrated a modified form of the invention wherein like or similar parts are indicated by numerals of the 300 series. This figure illustrates the simplest form of the invention and one wherein the multiple air chamber arrangement is not employed. The vault body includes the bottom 310, side walls 311 and end walls 312. The walls adjacent the open mouth are shouldered as at 320 and include inclined inside surfaces 321. An angular peripheral conforming seal support 322—341 bears upon said shoulder at 80 the lower outer edge. The cover 315—314 has the peripheral tongue 323 that seats in the cement seal 350, forcing the material outwardly as at 351 and upwardly as at 352. The casket is indicated by numerals 317 and 90 318.

The invention claimed is:

1. A vault structure including a top having a depending peripheral tongue offset inward an appreciable distance from the periphery, a vault body having a peripheral shoulder adjacent the open mouth thereof, said vault being arranged to receive and enclose a casket, form means peripherally enveloping the casket and operatively associated at its outer edge with the shoulder, and cement material supported and retained by the form means and extended laterally between the cover and upper end of the vault body and inwardly of the tongue for forming overhead and peripheral air chambers between the cover and casket and vault body and casket respectively. 95

100 2. A device as defined by claim 1 characterized by the inner wall of the vault body above the shoulder being inclined outwardly. 105

3. A device as defined by claim 1 characterized by the inner wall of the vault body above the shoulder being peripherally and longitudinally corrugated. 115

4. A device as defined by claim 1 characterized by the inner wall of the vault body above the shoulder being peripherally and longitudinally corrugated and inclined outwardly. 120

5. A vault structure including a top having a depending peripheral tongue offset inward an appreciable distance from the periphery, a vault body having a peripheral shoulder adjacent the open mouth thereof, said vault being arranged to receive and enclose a casket, form means peripherally enveloping the casket and operatively associated at its outer edge with a shoulder, and cement material supported and retained by the form means and extended laterally between the 125 130 135

cover and upper end of the vault body and inwardly of the tongue for forming overhead and peripheral air chambers between the cover and casket and vault body and casket 5 respectively, the ends of the body of the vault being flared outwardly and upwardly.

6. A vault structure including a top having a depending peripheral tongue offset inwardly an appreciable distance from the 10 periphery, a vault body having a peripheral shoulder adjacent the open mouth thereof, said vault being arranged to receive and enclose a casket, form means peripherally enveloping the casket and having its lower 15 outer edge operatively associated with the shoulder, and cement material supported and retained by the form means and extending laterally between the cover and upper end of the vault body and inwardly of the tongue 20 for sealing the vault.

In witness whereof, I have hereunto affixed my signature.
